BURNER FOR HEAVY FUELS

Ward J. Bloomer, Westfield, N. J., assignor to The Lummus Company, New York, N. Y., a corporation of Delaware

Application December 24, 1952, Serial No. 327,892

4 Claims. (Cl. 158—4)

This invention is an improvement on my prior inventions relating to fixed centrifugal or vortical fuel burning as generally set forth in applications for Patent Serial No. 66,445, filed December 21, 1948 and Serial No. 98,976, filed June 14, 1949, now Patents Number 2,560,074 and 2,560,076.

The present application is a continuation-in-part of my application Serial No. 151,023, filed March 21, 1950, now abandoned.

In the aforesaid cases I have disclosed an improved type of burner for various fuels such as oil, gas and pulverized solids, such as coal. In general, a vortex of air is established within an open-ended, annular or cylindrical tuyère by forcing the air at a relatively high velocity between the substantially tangentially disposed blades forming the tuyère wall. The fuel is introduced into this vortical column in either of two satisfactory ways. In one form the fuel is maintained in a reservoir surrounding the side wall of the tuyère adjacent the closed end and the incoming air passing over the fuel, entrains the fuel and carries it into the tuyère. Alternatively, a fuel distributing means is provided which extends through the closed end of the tuyère, and being spaced from the central axis, the fuel is introduced directly into the vortical column. This assures uniform distribution and avoids the resistance to the introduction of the fuel, by the rapidly rotating inner wall of the column. The atomization of the fuel and thorough dispersion into the column is completed in the tuyère and the combustible mixture is then discharged into a combustion chamber or throat spaced from the tuyère. The combustion chamber or throat serves as a radiant chamber to maintain uniformity of combustion, and the tuyère due to its spaced position and the flow of air through it, is maintained at a relatively cool temperature.

My present invention relates more particularly to an improved construction of burners which has a greater range of operation with respect to fuels in that it is particularly adapted to burn not only the gaseous and distillate fuels but also the heavy residual fuels which have a higher carbon ratio than distillate fuels. The burner is particularly effective in burning materials such as asphaltic residues. Asphalts, particularly from Venezuela deposits are not only difficult to burn but they have a further complication in that the ash is approximately 50% vanadium pentoxide (V_2O_5). The ash skeleton from a droplet generally forms a flyash which is not only externally wet and sticks to the boiler and superheater tubes but also attacks the brick work forming eutectic mixtures which tend to melt down the brick. Furthermore, the sticky vanadium slag grows in thickness until heat stresses crack the coating from its bond to the tubes forming flakes and clots which heat and soften and slide around the tube surface. These form obstacles in the gas stream and eventually a hard and clinker like mass throughout the tube bank forces a shut down for cleaning or retubing. It is recognized that slag deposit is caused primarily by particles of unburned or incompletely

2

burned atomized oil and particles of unburned unatomized oil.

My burner is particularly satisfactory for combustion of such asphaltic residues which exist in very large quantities in parts of the United States and particularly in the northern part of South America. By the proper introduction of the melted asphalt into the vortical column within the tuyère, I am able to obtain in an atomization such that the oil droplets are burned as a vapor so completely in the refractory throat of the burner that the particles of flyash have a size of the second order of magnitude i. e. infinite ratio of surface to mass, zero inertia and gas-like properties. They are completely airborne and are not thrown out in any deflected gas stream. With their infinite surface-mass ratio the flyash particles radiate extremely readily to tube surface and drop in temperature so fast as to be very much colder than the gas carrying them. As operated in my burner the flyash, if any, has a micron size of 100 microns or smaller and it does not build up slag deposits. Furthermore, there is no flame impingement on the brick work or tube surfaces, as there is no flame issuing from the burner throat, the intimate degree of atomization afforded by the vortex of the burner results in fewer shut downs for cleaning, higher effective temperatures and greater combustion economy.

My invention is thus particularly concerned with a modified burner apparatus whereby heavy residual fuels can be more effectively burned in a fixed centrifugal or tuyère type burner with greater atomization of the fuel and longer successful operating periods of the burners as well as the furnace.

Further objects and advantages of my invention will appear from the following description of preferred forms of embodiment thereof as more particularly shown in the attached drawings in which:

Fig. 1 is a substantially vertical central section through a portion of a furnace showing the general arrangement and location of the burner.

Fig. 2 is a diagrammatic central vertical cross section of the burner.

Fig. 3 is a front elevation of the burner shown in Fig. 2.

Fig. 4 is a partial vertical cross section of the burner with a modified form of tuyère skirt or baffle.

As a preferred form of embodiment my burner is particularly adapted for installation in the refractory side wall 19 of a furnace which may be a boiler, oil heater or other heat absorbing unit. Mounted on the side wall of such a furnace is a so-called burner plate 11, such burner plate carrying additional refractory having an opening 12 formed into the shape of a cylinder to receive the windbox or enclosure 14 and also other refractory formed into a cylindrical combustion chamber 15. The windbox extends rearwardly into an air duct generally indicated at 16 which is adapted to be connected to a source of air under a slight pressure, such air being preferably preheated for the combustion of asphalt and other very heavy fuels. The windbox 14 also extends forward nearly into contact with the refractory 15a which forms the rear wall of the combustion chamber.

The burner assembly includes a tuyère 18 of generally cylindrical shape, being open at one end and having a frusto-conical plate 20 surrounding the orifice. The side wall of the tuyère is provided with a plurality of generally tangential shallow vanes or blades 22 extending throughout the entire length of the tuyère. For economy, they may be stamped out of the tuyère wall, but it will be understood that they may be separate blades, and they may overlap, or be streamlined as desired. These blades form a plurality of elongated substantially rectangular air inlets 23 disposed between the adjacent blades 22. The rear of the tuyère is closed by an end wall 24.

The face plate 20 of the tuyère is preferably provided

with a double row of small openings 20a surrounding the orifice for the free passage of air from the windbox 14, such air passing across the face plate in rear of the refractory 15a whereby the face plate 20 is kept cool. The frusto-conical face plate 20 is integrally mounted to the edge of the tuyère blades and is freely movable with the tuyère in the windbox 14 so that the entire burner assembly as shown in Fig. 2 may be moved into and out of position as desired. The windbox 14 has a shoulder 14a against which a packing ring 25 is placed so that the frusto-conical face plate makes a substantially gas tight seal at the edge of the windbox 14.

The tuyère 18 may be provided with a dual fuel supply. For the feed of a heavy liquid such as asphalt, I prefer to use a fuel distributing means consisting of a plurality of tubular nozzles 30 which project through the closed end 24 of the tuyère about $\frac{1}{2}$ inch and are conveniently chamfered at a 45° angle with the vertical. In each case the lowermost edge of the nozzle projects furthermost into the tuyère. These nozzles are fed from a common distribution ring 32 which in turn is supplied from a fuel line 34.

The six fuel feeding nozzles 30 extending into the closed end of the tuyère 18 have their discharge openings spaced uniformly a substantial distance from the closed end wall 24 and from the oppositely disposed slots 23 of the side wall, the said openings defining a plane perpendicular to the longitudinal axis of the tuyère and being uniformly spaced on a common circle.

In addition I prefer to use a secondary fuel feed distributing pan or reservoir 46 of a cup shape closely fitting the side wall of the tuyère and spaced a small distance away from the closed end 24 of the tuyère. As shown in Fig. 2 the side of the pan 46 embraces the edge of the tuyère blades in such a manner as to form a series of peripherally disposed triangular openings through which the fuel is drawn into the tuyère by the air as it passes between the blades. The secondary fuel reservoir is interconnected by fuel line 45 to a suitable secondary source of fuel which may be gas or a distillate. Both fuel lines 34 and 45 pass through a removable door 47 held by quick detachable lugs, the fuel lines having unions 48 so that quick detachment and re-attachment of the burner can be accomplished. The feed systems may be used simultaneously or alternatively and either liquid or gaseous fuel may be fed in either system.

The operation of the burner for burning the gas or distillate fuel includes forcing the air from the duct 16 into the windbox or enclosure 14 and thence across the blades and into the combustion chamber 15.

The continuous introduction of air through the convergent air paths establishes a rotating mass, the centrifugal effect of which is to establish a relatively dense shallow layer generally indicated at "X" adjacent the side wall of the tuyère, the inner wall of such layer being substantially parabolic with its vertex below the closed end of the tuyère 24. This layer may be considered to be a substantially hollow rotating column which is cylindrical on the outer wall and truncated parabolic on the inner wall or surface. The fuel is introduced to this layer to be entrained in the rotating air mass and is given a spiral and helical path in the tuyère before being discharged with air as a combustible mixture into the combustion zone.

Normal velocities of the entering air are approximately 70 ft./sec. The static head of air is thus converted to rotational energy so that inside the tuyère the air is caused to rotate in forced vortex motion as a parabolic of revolution. Due to the high velocity of the air and the rapid rotation of the mass, the column is open throughout its length and has a substantial vacuum in the central portion forming a line of force into the end of the tuyère perpendicular to the closed end 24. It is observed that the column actually forms a circular intercept with the center of the end wall as indicated at 37. It is impor-

tant for my purposes that the velocity of the air be such as to maintain this column open throughout. The fuel-air thus discharges as an annulus solely adjacent the side wall of the tuyère, into the throat 15.

It is desirable to avoid a slow moving column of air in the tuyère as to cause mere turbulence or a reverse of flow that would throw out fuel from the center. It has been my observation that a minimum velocity of 35 ft./sec. is necessary to establish a suitable vortex and generally I prefer velocities that are as high as 100 ft./sec. although this results in a very substantial pressure drop. The greater the velocity, the tighter or more nearly cylindrical is the vortex and thus the greater the fuel path and the greater the shearing and mixing. With 70 ft./sec. which is preferably used, I estimate the effect of the centrifugal force to be about 600 times gravity, with a 6 in. diameter tuyère.

An outstanding characteristic of this vortical atomization is that combustion efficiently increases with an increase in velocity or firing rate. First, higher flame temperature improves ignition and flame stability, and second, a change in the force balance increases the ratio of outward centrifugal force to inward viscous drag force resulting in a further decrease in oil particle size.

It has proved to be a characteristic of the burner that when the air pressure drops, the oil pressure indicator always shows an increase. The violence of the center vortex draws the oil from the feed nozzles 30 to the whirling ring 37 and when the central vacuum lessens, the oil is not pulled so strongly. This has the advantage that the manifold pressure required for multiple burners is only that needed for accurate throttling. Control may thus be readily accomplished by conventional pressure control instruments reset by the temperature of a coil outlet. Calibrated orifices will of course be inserted in the various feed lines to evenly proportion a similar amount of oil to each burner.

The burning zone is within the throat or combustion chamber 15 so spaced from the end of the tuyère as to relieve the tuyère of the necessity for withstanding combustion temperatures. The spacing of the combustion zone 15 from the mixing zone of the tuyère is accomplished by maintaining the flow of air between blades in opposition to the centrifugal effect of the column whereby the fuel-air column "X" moves outwardly into the throat or combustion chamber. By properly arranging the blade angle and by maintaining the desired air inlet velocity and by introducing the fuel adjacent the closed end of the tuyère there is an intimate dispersion of the fuel in the air. In addition heat from the combustion chamber tends to radiate into the substantially open column to produce a highly effective partially heated fuel air mixture by the time it discharges into the combustion chamber.

The distance of the combustion zone within the refractory throat 15 is controllable through variation of the relative dimensions of the tuyère and throat, the ratio of tangential to axial velocity of the air-fuel mix as it enters the combustion chamber, the linear velocity of this mixture as it emerges from the tuyère annulus. It is also dependent on the fuel-air ratio. This ratio is a function of the air pressure in the windbox 14 and of the initial velocity of the air column impressed upon the burner before the air column reaches the entrainment zone adjacent the closed end of the tuyère. It is also dependent upon the ratio of the diameter of the tuyère 18 to the length of the blades 22. For example, doubling the tuyère diameter and halving the blade length, while having the same blade area, pressure drop and air capacity in the burner, provides four times the cross sectional area in the tuyère outlet orifice. For this reason the linear velocity is reduced in square root proportion to the increase in diameter and the pattern of the combustion zone would thus be varied accordingly by variation of the diameter-length ratio. Ordinarily I find that a ratio of greater length than diameter is the most advantageous for atomization due to the pro-

portionately greater energy for atomization which exists with the smaller radius.

The effect of the rapidly rotating vortex within the tuyère 18 on liquid fuel from the nozzles 30 will thus be appreciated. It has been observed that the line of force into the closed end of the tuyère is due to a negative pressure of nearly 25 inches of water which violently draws in flue gas establishing a path partially across the bottom and thence outward along the definition between the vortex and the rotating air-oil envelope. This line of force then extends out of the tuyère and rolls on itself as an inner eddy in the refractory throat or combustion chamber 15. At such point this eddy of air and fuel is ignited and flame stabilization is established.

The inner eddy creates a suction within the flame which tends to draw each particle of flame or remaining unconsumed air and fuel toward the axis of the flame. The outer eddy serves for initial ignition with reduced air supply providing a rich mixture and then at normal air flow, provides for re-ignition and stability. If the oil viscosity at atomizing temperature is too high, the heaviest particles are thrown out centrifugally and are stagnated in this eddy forming a ring of coke within the throat. This may be corrected by raising the air temperature or the oil temperature, with the air temperature predominating in securing the proper low oil viscosity for efficient shearing or atomizing.

Within the tuyère it may be shown that the center line of force, inward to the closed end 24 of the tuyère, defines the boundary between the vortex existing as a vacuum and the rotating air mass existing under pressure. The outward defining line of force then creates an eddy within the tuyère adjacent the closed end which draws the fuel and air inwardly and down.

The oil discharge from the nozzles 30 is thus effected not only by this inwardly moving fuel gas and eddy created by the outward spiralling first line of force but also from the rapid rotational effect of the vortex. A strong shearing action results. This is generally represented in Fig. 3 by the suggested path 35 of an oil droplet discharging from one of the nozzles 30. The oil is drawn violently into the eddy created by the outwardly spiralling first line of force and is then swept against the burner end wall 24 and toward the center where the oil rings the vortex interception 37 with the end wall. Here it achieves enough body to be acted on by centrifugal force imparted by friction with the rotating air. The fuel is then thrown spirally outward and forward passing through laminar layers of air, all whirling at different circumferential speeds. The fuel is thus sheared as though it were fed between two wheels of different rotation and homogenized therein.

It is of course to be understood that with a plurality of nozzles 30 as for example six equally spaced in a tuyère of seven inches diameter, there is such an overlapping of the fuel paths so that the discharge of combustible material appears uniform. I have found it essential that the nozzles 30 be spaced on a circle which comes between the walls of the vertical column "X" for I find that with the high velocity of rotation there is a substantial resistance by the inner wall of the column to the introduction of a liquid fuel which causes an erratic distribution. There is a minimum of resistance in the area between the inner and outer walls of the column.

I also find that with the heavy fuels having a carbon content greater than distillate fuels, there is some tendency of segregation with the heavy portions designated "Y" thrown to the outer wall. It will be apparent that the lightest oil is thus on the inner portion of the vortex and due to the heat radiation and flow of flue gases the light oil is atomized quickest and in a path spiralling outward from the vortex circle. The residue being heavier, is subjected to a greater centrifugal force and being further outward from the center axis is sheared to a greater extent during its greater residence time and longer spiral

path. As a result, it is estimated that the particles are broken down generally into 100 micron size or less with a resulting very high temperature flame.

I have found that even with careful distribution of oil within the column walls, and even with the desired high velocity of air, the asphalt feed sometimes tends to deposit droplets on the blades and thus cause premature coking. It is apparent that the larger oil particles are thrown centrifugally outward thus striking the inner blade surfaces. There they are driven by the slant of the blades to the outer edge but at this point, due to the entering air, an eddy exists of quiet liquid and this rapidly cokes. The main air stream returns some of the droplets through the blades but it plasters more against the back of the burner face 20. This cannot be tolerated since it forms coke and partly closes the holes 20a on which reliance is placed for air cooling. It has also been found that the velocity of the air entering the blades adjacent the open end of the tuyère is considerably less than the velocity through the blade adjacent the closed end of the tuyère.

With the heavy fuels, I have thus found it desirable to utilize a skirt or baffle generally indicated 28 with a cylindrical portion uniformly surrounding the major part of the tuyère and surmounted by the conical portion 28a which connects the cylindrical portion with the outer part of the tuyère blades 22. By virtue of the pressure drop thus imposed on the air passing from the windbox through the skirt passage to the blades, a controlled velocity of air is established through the blades which thus enters along planes which are substantially transverse to the tuyère axis. This not only assures reentrainment of any liquid which might become thrown out by the centrifugal force but also substantially prevents disentrainment by assuring the desired velocities along the blade length.

A good tuyère operation is secured with a proper balance between the centrifugal force on the atomized particles which throws them toward the blades and therefore toward the blade entries (for fouling) on the one hand and the centripetal component of the viscous drag of the incoming air on the other hand. In such case the particles can be made to rotate in a circular path in the burner so as to reduce blade impingement.

In some cases by proper dimensioning for suitable entering velocities to the blades, it may be possible to utilize the windbox 14 as the skirt but generally it is easier to provide the particular desired skirt size for various burners rather than to change the windbox for each different operating condition. Furthermore, I provide space for the air for the openings 20a in the face plate which serves to cool the face plate during operation. In other words, the rear refractory 15a in the combustion chamber is normally spaced about $\frac{1}{4}$ inch from the face plate 20 and substantially overlapping it and by passing approximately 2-4% of the air through the openings 20a and under the projecting end of the refractory I can be assured of a long-lived face plate. The refractory shield is generally satisfactory although I have also used a spaced alloy shield as described in my copending application Serial No. 98,976, now Patent Number 2,560,076. The alloy shield is unsatisfactory in the presence of vanadium containing fuels because of catalytic oxidation. The use of the shield and the cooling air has reduced the

temperature of the face plate from 1300-1400° F. to a temperature in the range of 700° F. I have also described in my said Patent No. 2,560,076, a form of skirt which surrounds an intermediate part of the tuyère and may be made of such diameter and position that differential velocities of air through the respective portions of the blades are obtained. With a burner where the major problem is to prevent dis-entrainment and to assure re-entrainment, the skirt must be substantially coextensive with the tuyère. It will be apparent that a great many varieties may be used but for practical purposes,

I have found the structures of Figs. 1 and 4 to be most effective and least complicated.

In Fig. 4, the tuyère 18 having the typical front face 20, is provided with a multiple diameter skirt 38 having a first conical section 39, a cylindrical portion 40 and a closing cone 41. This type which diminishes in diameter in an outward direction tends more effectively than that shown in Fig. 1 to increase the velocity through the blades nearest the open end of the tuyère, and thereby prevents disentrainment of fuel from the air column.

Other constructions have been tried with more or less success including a right cone, a cylinder, and an inverted multiple diameter skirt of the type shown in Fig. 4 but sealed with respect to the closed end wall of the tuyère.

I have also used directional vanes 43 as shown in Fig. 3 by which the entering air which normally passes axially with respect to the tuyère as it moves through the windbox is given an angular component tending to give a more nearly tangential inlet between the blades. It will also be apparent that streamlining of the blades and other parts can be utilized in the interest of saving pressure drop. The structure as shown in Fig. 1 however is commercially satisfactory although the detailed improvements will be used if their economy of operation exceeds the cost of making the changes.

The use of preheated air with residual fuels is quite important from the standpoint of coke free operation. Where fine atomization in the order of 100 microns or less is desired, the fuel must be in condition for intimate dispersion in the air. It has been my experience that a viscosity range of 20 to 50 centistokes is most effective and with residual fuel oils the temperature of the air should be from 200-250° F. With asphaltic residues, the temperature of the air of from 350-450° F. will give approximately the same results. The preheated air, of course, increases the efficiency of the burner.

A typical installation of this type had substantially the following dimensions:

Capacity	10 MM B. t. u./hr.
Tuyère diameter	9".
Tuyère height or length	12".
Fuel	Asphalt.
Gallons/hr.	70.
Air velocity	96'/sec.
Air temperature	400° F.
Air pressure	7" water gauge.
Number of jets	6.
Inside diameter of jets	0.152".
Number of blades	72.
Width of blades	.390".
Blade opening	3/32".

The range of burner sizes for various duties is generally found in the following table, it being understood that by varying the air velocity, a range of operation of from 70 to 140% may be obtained in any burner.

Capacity	1 MM ¹	4.8 MM ¹	7.2 MM ¹	10.6 MM ¹	12 MM ¹
Tuyère Diameter	3	7 1/2	7 1/2	10	8.7
Tuyère Length	3	6	9	9	12
Curb or Chamber Diameter	10	20	22 2/3	28	30
Curb or Chamber Length	18	20	27	27	30
Fuels, Gals. per hour-Bunker "C"	7 1/2	32	48	72	80

¹ MM is equal to 1,000,000 British thermal units.

A closed flame pattern can be obtained within the combustion chamber if it has the critical dimensions characteristic of the chamber in Fig. 1. The chamber should not be less in diameter than about 1 1/2 times the diameter of the tuyère opening and it should be not greater than 4 times, and preferably 3 times the diameter of the tuyère opening. In length, the combustion chamber should be nearly as long as its diameter.

I have not found it necessary to use secondary air for

combustion purposes. However, many furnace operators choose to introduce secondary air for various reasons. This may be introduced at any desired point for any of the desired reasons such as cooling bridge walls, etc.

5 The burner is normally designed for no excess air operation at 6" water gauge and operates at a maximum of 20 percent excess at nine inches, normal rating. The burner has an operating range of 70% capacity to 125% capacity. For lower velocities of air, the flame pattern becomes ragged and uneven with possible formations of coke with heavy fuel feed.

An important feature of the direct combustion of asphalt will be apparent from a typical disposal problem. In the particular case, it was desired to dispose of 200 15 barrels per day of asphalt from a propane extraction process. This was blended with an equal amount of distillate having a value of \$3.60 per barrel. The resulting fuel was worth \$1.80 per barrel. The saving in direct burning of the asphalt is thus the saving in downgrading 20 the distillate or \$360.00 per day (over \$100,000 per year). In addition there is the saving of maintenance and other costs applicable to customary asphalt burning.

There is also the advantage, however, that alternate 25 fuels can be used. Depending upon the season and the availability of fuel, the operator may choose to run gas, distillate, reduced crudes, or even the asphaltic residues. The burner can burn simultaneously two or more mixtures, the flame continuing to be short, brilliant, smoke free and ash free. The increased flame temperature makes 30 possible higher heat input rates and further reduces costs of allied equipment. The burner is shown in horizontal position in Fig. 1 but it has also been shown in vertical position in the companion copending cases, Serial No. 66,445 and Serial No. 98,976, now Patents No. 2,560-35 074 and 2,560,076. It will work equally well in angular positions due to the fact that the velocity of air is so great that the established gravitational effect of the vortex is little influenced by gravity.

A port 50 is provided thru the back refractory surface 40 surrounding the burner face. A lighted gas torch with no air premix is inserted in the port and completes its combustion on the back of the whirling air pattern in the refractory throat, remaining permanently lit. When fuel gas is admitted to the burner, combustion is immediate. 45 Because the fuel gas-air ratio is substantially stoichiometric the combustion is colorless and transparent and evident only from the radiant refractory throat.

Recommended practice is to then cut over to fuel oil to flush and warm the feed lines and valving. It was 50 possible with a vigorous pilot flame to omit the intermediate step of gas firing, igniting the highly atomized fuel oil even in a cold refractory throat, though best practice is to provide for initial gas firing.

Asphalt then follows the fuel oil and burns with an 55 even more dazzling white incandescent flame because of its increased viscosity and higher carbon residue.

Prior to a shutdown fuel oil is again resorted to for flushing the burner and lines. In cold climates the burner lines may be purged by the gas.

60 Where it is forbidden to light a torch outside the furnace the gas-electric method of ignition may be used for starting or continuing the pilot light.

While I have shown and described a preferred form of burner in accordance with my invention, I am aware that 65 modifications may be made thereto which are within the scope and spirit of my invention.

I claim:

1. In a liquid fuel burner, an open ended hollow 70 annular tuyère having a closed end wall, and a side wall 70 having a plurality of fixed substantially tangential blades extending throughout the major part of said side wall and forming inwardly convergent air paths, an enclosure surrounding said tuyère, means for supplying an air current to said enclosure and through said air paths between 75 said blades to establish a vortical air column in said

tuyère, fuel supply means adjacent the closed end wall of said tuyère adapted to communicate with the vertical air column whereby said fuel is entrained in said column and discharged through the open end of the tuyère, said fuel supply means including a plurality of nozzles extending through the closed end wall of the tuyère in spaced relation to the side wall and at such a radial distance from the center that the vertical air column therein normally covers the discharge openings, and a fuel distributing pan surrounding the closed end wall of the tuyère, the wall of said pan forming with the edge of the blades a plurality of peripherally spaced fuel passages, and separate conduit means to supply fuel to said nozzles and pan.

2. In a liquid fuel burner, an open ended hollow cylindrical tuyère having a closed end wall, and a side wall having a plurality of fixed substantially tangential blades extending throughout the major part thereof and forming inwardly convergent air inlet paths, an enclosure surrounding said tuyère, means for supplying air to said enclosure and through said air paths between said blades for forming a hollow, swirling, forwardly moving vortex of air in said tuyère adjacent the side wall, a plurality of fuel feeding nozzles extending a short distance through the closed end wall of the tuyère in spaced relation to the side wall and at such a radial distance from the center that the portion of the forwardly moving vortex of air adjacent the closed end wall in the tuyère normally covers the nozzle openings, and an annular skirt within the enclosure surrounding the tuyère and sealed with respect to the open end thereof, the other end of the skirt being spaced from the tuyère to receive the air entering the enclosure and direct it through the tuyère inlet paths, the cross sectional area of the skirt portion adjacent the open end of the tuyère being less than that at the closed end of the tuyère whereby the velocity of the air entering the tuyère is increased near the open end to restrain fuel disentrainment.

15
30
35

3. In a liquid fuel burner as claimed in claim 2 in which said annular skirt has multiple cylindrical sections of different diameter which are joined by conical sections to each other and to the open end of the tuyère.
- 5 4. In a liquid fuel burner, an open ended hollow cylindrical tuyère having a closed end wall and a side wall having a plurality of fixed substantially tangential air inlet slots extending throughout the major part thereof and forming inwardly directed air inlet paths, an enclosure surrounding said tuyère means for supplying air to said enclosure and through said air inlet paths for forming a hollow, swirling, forwardly moving vertical column of air in said tuyère adjacent the side wall thereof, annular baffle means within the enclosure extending the length of the air inlet slots and in the path of the supplied air to maintain a velocity of air through the air inlet paths at all parts of the vertical column at least equal to the velocity adjacent the closed end of the tuyère to prevent disentrainment of fuel from the air column, liquid fuel feeding means including a plurality of nozzle openings disposed within the interior of the tuyère a short distance from the closed end wall and at such a radial distance from the center that the portion of the forwardly moving vertical column of air adjacent said closed end wall in 20 the tuyère normally covers the nozzle openings, and means to supply liquid fuel to said nozzle openings whereby fuel is entrained in said vertical column of air.
